DESIGN FOR A BOOK MATCH HOLDER AND DISPENSER OR SIMILAR ARTICLE

James Alva Coon, Ossining, N. Y.

Application March 4, 1948, Serial No. 144,896

Term of patent 14 years

(Cl. D48—28)

To all whom it may concern:

Your petitioner, James Alva Coon, a citizen of the United States and a resident of Ossining, New York, whose post office address is 49 Croton Avenue, Ossining, New York, prays that Letters Patent may be granted to him for the term of 14 years for the new, original, and ornamental Design for Book Match Holder and Dispenser or Similar Article, set forth in the following specification, reference being had to the accompanying drawings forming a part thereof, wherein:

Fig. 1 is a perspective view of a book match holder and dispenser or similar article embodying my invention with the door thereof shown in open position,

Fig. 2 is a top perspective view thereof looking down from the top with the door in its closed position,

Fig. 3 is a side perspective view taken on line 3—3 of Fig. 2,

Fig. 4 is a front perspective view taken on line 4—4 of Fig. 2, and

Fig. 5 is a bottom plan view, taken on line 5—5 of Fig. 1.

The characteristic features of my design reside in the portion shown by means of full lines in the drawing.

I claim:

The ornamental design for a book match holder and dispenser or similar article, as shown and described.

JAMES ALVA COON.
